HUGHES TOOL COMPANY, OF HOUSTON, TEXAS, A CORPORATION OF TEXAS

DISK BIT

Application filed March 22, 1930. Serial No. 437,953.

We contemplate the provision of a straight shaft but with bushings thereon, arranged in offset relation to get the desired offset position on the drill of the separate cutters.

5 In the drawing herewith wherein we have shown earth boring drills equipped according to our invention, Fig. 1 is a side elevation of a disk bit embodying the invention.

Fig. 2 is a transverse section on the plane 10 2-2 of Fig. 1.

Fig. 3 is a side elevation of a drill equipped with cutters mounted according to our invention and illustrating a slightly different embodiment of the said invention, the upper 15 part of the drill being in central vertical section.

Fig. 4 is a transverse section on the plane 4-4 of Fig. 3.

In carrying out the invention we have illustrated a drill bit of the usual construction having an approximately cylindrical head 1, the upper end of which is reduced in diameter and threaded at 2 for engagement with the drill collar. The head 1 has a pair of 25 downwardly extending legs 3, the lower ends of which form a support for the disk shaped cutters 4.

As will be seen from the drawing, the drill head has an axially extending passage 5 therethrough for the flushing fluid which is adapted to conduct the flushing fluid directly upon the cutters.

In Figs. 1 and 2 we have shown the legs 3 of the cutters offset slightly relative to each 25 other, one leg being slightly to one side of the central axis of the bit, and the other leg being offset to the opposite side of the said axis. The inner faces 6 of the legs are flattened and these flattened faces are parallel 40 with each other to furnish a lateral support for the bushings 7 upon which the cutters are mounted. Each leg has adjacent the lower end an opening 8 therein to receive the shaft 9. This opening is countersunk at 10 at its outer end to receive a washer 11 through which the end of the shaft may project.

The shaft 9 is cylindrical and extends through the legs of the cutters in a line cutting the plane inner faces of the legs at an 50 angle not perpendicular thereto, so as to ob-

tain the offset mounting of the cutters which is desirable. The ends of the shaft are reduced in diameter at 12 to engage within the opening in the washer 11, and the end of the reduced portion is adapted to be upset or riveted over the washer as shown in the drawing so as to lock the shaft securely in position after the cutters have been mounted thereon.

Each cutter is mounted upon a bushing 7 previously referred to. The bushing is cylindrical on the bearing portion thereof, the outer end of the bushing being provided with a radial flange 13 to bear against the inner face of the leg. Said bushing is adapted to be held in non-rotatable position on the shaft by means of a set-screw 14 extending through the leg and engaging within a recess in the bushing. Each bushing is set at an angle to the shaft upon which it is mounted by forming a shaft-receiving opening 15 therein, extending in a slightly diagonal line through the bushing, said opening thereby being a line not truly along the axis of the bushing. This shaft-receiving opening is 75 thus formed so that the cutters 4 may be parallel with each other, and yet set in the head of the bit in a position offset from each other, as will be understood from Fig. 2.

The cutters are beveled at 16 on their outer faces, the forward faces 17 thereof being flattened toward the cutting edge to present a cutting edge along the forward side thereof. There is a hub 18 on each cutter extended inwardly so as to partially protect the shaft 85 9 from the action of the flushing fluid.

In Figs. 3 and 4 we have obtained the offset arrangement of the cutters in a slightly different type of head. The legs 3' in this cutter are arranged directly opposite to each other, 90 the inner faces 6' being parallel and oppositely arranged. The shaft 9 extends through the legs of the cutter in a line perpendicular to the inner faces 6', said shaft being otherwise held in position in the same manner as 95 in the first embodiment.

In this arrangement, however, the bushings 7' are formed with the outer flanged end 13' of approximately wedge shape, one side being thicker than the other, thus placing the cut- 100

ters 4 in a position to offset from each other. The openings through the bushings to receive the shaft are in the same diagonal position relative to the cutters as is the case in Fig. 2.

5 In other respects the two arrangements are approximately the same. The cutters are mounted on the bushings in the same manner parallel with each other, and rotated on the bushings supported on the shaft and held in 10 position by cap-screws 14.

The advantages of the construction lie in the fact that we are enabled to mount the cutters upon a straight cylindrical shaft supported at both ends in the legs of the bit.

15 The cutters are adapted to rotate smoothly on their bushings and in an offset position as is desired. The strength of the structure is materially increased, and the cost of construction is also cheapened so that we are enabled 20 to supply a bit of this character at a price within the means of the ordinary operator.

What we claim as new is:

1. A drill bit, including a head, two opposed supports thereon, a straight cutter shaft supported at its ends in said supports, bushings secured non-rotatably on said shaft, and cutters mounted on said bushings, said bushings being formed with diagonal shaft-receiving openings to position the cutters in offset relation, whereby one will contact with the wall of the hole at one side only and the other at the opposite side only.

2. A drill bit including a head, two spaced downwardly extending legs thereon, the inner opposed faces thereof being flattened, bushings having heads thereon fitting against said faces, the inner ends of said bushings being spaced slightly apart, said legs and bushings having aligned openings diagonally 30 through said bushings, a straight shaft through said openings, means securing the heads of said bushings to said legs, and cutters rotatable on said bushings and offset laterally on opposite sides of said shaft.

3. A drill bit including a head, two spaced downwardly extending legs thereon, the inner opposed faces thereof being flattened, bushings having heads thereon fitting against said faces, the inner ends of said bushings 30 being spaced slightly apart, said legs and bushings having aligned openings diagonally through said bushings, a straight shaft through said openings, means securing the heads of said bushings to said legs, disk shaped cutters rotatable on said bushings, said cutters bearing against the heads of said bushings on one face of each cutter and hubs on the adjacent faces of said cutters flush with the inner ends of said bushings.

30 In testimony whereof, we hereunto affix our signatures, this the 12th day of March, A. D., 1930.

HAROLD W. FLETCHER.
FLOYD L. SCOTT.
